DESIGN FOR AN END COVER FOR A SUCTION CLEANER CASING OR SIMILAR ARTICLE

Henry Dreyfuss, New York, N. Y., assignor to The
Hoover Company, North Canton, Ohio, a cor-
poration of Ohio

Application October 25, 1946, Serial No. 134,266

Term of patent 14 years

(Cl. D9—2)

To all whom it may concern:

Be it known that I, Henry Dreyfuss, a citizen of the United States, residing at New York city, in the county of New York and State of New York, have invented a new, original, and ornamental Design for an End Cover for a Suction Cleaner Casing or Similar Article, of which the following is a specification, reference being had to the accompanying drawing, forming a part thereof.

In the drawing:

Figure 1 is a top plan view of an end cover for a suction cleaner casing, showing my new design;

Figure 2 is a side elevational view;

Figure 3 is a front elevational view; and

Figure 4 is a perspective view of the same.

I claim:

The ornamental design for an end cover for a suction cleaner casing or similar article, sub-
stantially as shown.

HENRY DREYFUSS.
